E. B. SPENCER

WASHING MECHANISM

Filed Aug. 3, 1920

UNITED STATES PATENT OFFICE.

EARL B. SPENCER, OF PASADENA, CALIFORNIA.

WASHING MECHANISM.

Application filed August 3, 1920. Serial No. 401,013.

To all whom it may concern:

Be it known that I, EARL B. SPENCER, a citizen of the United States, residing in the city of Pasadena, county of Los Angeles, 5 and State of California, have invented certain new and useful Improvements in Washing Mechanisms, of which the following is a specification.

My invention relates to washing mechanisms, and more particularly to a washing mechanism including two co-operating suction members, operable relative to each other, in connection with clothes to be washed, in a tub or other basin, and adapted 15 to cause the water or washing fluid to be forced back and forth through said clothes.

In order to explain my invention, I have illustrated on the accompanying sheet of drawings a device, embodying my invention, 20 which is automatic, operated by a water motor, and in which the co-operating suction members are arranged one within the other, concentrically positioned, and both operatively connected with the motor. I have 25 shown a water motor of the type in which water simply passes through the motor, operating the parts thereof, and then passes out to be used, if desired, for other purposes, as in sprinkling. I have also shown a portable 30 device which can be lifted into and out of the tub or basin containing the clothes to be washed.

I will now describe in detail the mechanism used for illustrative purposes.

35 Figure 1 shows my invention, as here embodied, in vertical sectional view;

Figure 2 shows a bottom plan view of the suction members thereof;

Figure 3 is a vertical sectional view 40 through a part of the water motor;

Figure 4 is a fragmentary, sectional view, of a detail.

Figure 5 is a fragmentary, sectional view showing the valve moved; and

45 Figure 6 is a cross sectional view on line 6—6 of Fig. 3.

In the drawings, 1 designates a basin with the clothes, 2, and the washing fluid, 3, therein, as shown. Two suction members 4 and 5, are mounted one within the other concentrically, and are connected, respectively, to the body or cylinder, 6, and the plunger, 7, of a water motor, whereby said suction members are moved relative to each 55 other in a manner which will be well under-

stood, as the motor is operated. The member 4 is provided in its top with a simple ball check valve, 8, as clearly indicated in Fig. 4, which permits air to escape from under the member 4.

The cylinder 6 of the motor, is provided with two tubular extensions, 6^a and 6^b, with which are connected, respectively, the supply and the outlet hose, 9 and 10. The supply pipe 9 can be connected with any suitable water supply, under pressure, as with the usual water outlet of a city supply, while the outlet pipe 10, can be connected with any suitable place of discharge, or with a sprinkling means, as desired. I do not 70 claim the water motor as my invention, having simply shown it as one simple and practical motor means for operating my co-operating suction members.

Referring to Fig. 3, however, I will describe the plunger mechanism of the motor in brief, in order to show how my suction members are operated by this type of motor. The piston body 11, has two tubular extensions, 12 and 13, which fit closely within and move in the tubular extensions 6^a and 6^b of the cylinder. A sliding valve member 14, in said piston, controls the direction of the water through the piston and determines whether the piston is moved up or down. Assuming that the water is entering through supply pipe 9, and down through the tubular extension 12, as shown in Fig. 3, it passes through the port, 15, into the lower part of the cylinder, and thus forces the piston 11 and its extensions 12 and 13, upwardly until the spring 16, over the valve member 14, engages the upper end of the cylinder 6, and thereby forces the valve member 14 down across the port 15, as in Fig. 5, whereupon the water enters the cylinder above the piston and forces it downwardly until the pins, 17, 17, on said piston, engage with the spring-supported washer, 18, Fig. 1, and again raises the valve member 14, to direct the water into the cylinder below the piston. The movement of the valve member 14, also controls the outlet of the water from the cylinder, for as the piston is forced up, the water above the piston is forced out through the tubular member 13 and outlet pipe 10, and as the piston is forced downwardly, the water below the piston is also forced out through the same outlet, as will be under- 110

stood. Inasmuch as this is a well known type of water motor, it need not be further described in its details.

The plunger 7 being attached to the suction member 5, and the cylinder body being attached to the suction member 4, it will be clear that the two suction members are moved apart and then moved toward each other as the piston and cylinder are moved 10 relative to each other by the water under pressure passing therethrough.

The open sides or bottoms of the suction members 4 and 5 set down upon the submerged clothes, in the manner indicated, and 15 the water supply for the motor is turned on and the movements of the suction members commence. As the outer member 4 starts up and the inner member 5 starts down to the position indicated in broken lines, the action 20 is to cause the water under member 5 to be forced out and also drawn out from under said member 5, and through the clothes, to fill up the vacuum effect caused in the outer member 4, as it and the inner member move 25 apart. When they are moved together, the displacement in the larger or outer member, caused by the in-moving inner member, forces the water out from under the outer member and draws it up under the inner member. Thus by the alternate movements 30 of these suction members, the water is forced back and forth through the clothes upon which the device sets. In actual use, the air is practically all forced out from under the 35 outer member 4 and suds will be seen escaping through the valve 8 on the down stroke of said outer member 4. The device will continue to thus operate until the water supply to the motor is turned off, or the device is lifted bodily from the tub or basin, and even then the suction members will continue to be moved by the motor, if the water supply be not turned off.

Thus I have provided a simple, practical, 45 portable, automatic washing mechanism which can be set into a basin containing clothes and a washing fluid, and started to operation and left to operate automatically so long as the motor continues to operate, 50 and while I have shown only one embodiment of my invention for illustrative pur-

poses, I am aware that other embodiments thereof can be made and that changes in details and arrangements can be made without departing from the spirit of my invention, and I do not, therefore, limit my invention except as I may be limited by the hereto appended claims.

I claim:

1. In a device of the character referred to, two suction members of bell-like form mounted one within the other, each of said members being movable relative to the other, and power means having two elements movable relative to each other in operation and 60 connected, respectively, to said suction members, whereby said members are positively and mechanically operated simultaneously toward and from each other, for the purpose indicated.

2. In a device of the character shown and described, two suction members of inverted cup-like form with their under sides open and mounted one within the other and movable simultaneously in opposite directions 75 up and down, one of said members having a valve-controlled outlet in its wall, and power means connected to said suction members and operable to move them simultaneously and alternately in opposite directions up 80 and down, substantially as described.

3. In a device of the character referred to, two suction members having open lower sides and closed upper sides and mounted one within the other with a space between 85 said members, a cylinder connected with the outer suction member for moving the same, a piston within said cylinder and connected with the inner suction member for moving the same, and means for connecting 90 an operating fluid to said cylinder, with valve means, for alternately directing said fluid to opposite sides of said piston, whereby to cause the operation of said suction members in opposite directions, alternately 95 up and down, substantially as described.

Signed at Pasadena, Los Angeles County, California, this 29th day of July, 1920.

EARL B. SPENCER.
